RAILWAY-HIGHWAY GRADE CROSSING
WARNING SIGNAL

Marion G. Slawson, Girard, Kans.

Application October 23, 1939, Serial No. 300,831

4 Claims. (Cl. 40—133)

This invention relates to a railway-highway grade crossing warning signal, and it has for its object to provide an improved device of this character comprising parts of such a nature and so correlated that the resultant structure may be economically manufactured, will comprise a limited number of moving parts, and those of a rugged and reliable nature, and one in which only a small amount of current is required to operate the same.

More specifically, the invention comprises an improved article of this nature, in which the warning elements consist of lights arranged to be flashed in succession and in such order as to simulate the swinging of a lighted lantern crosswise of the highway. It is a further object of the invention to provide a signal of this character, the body portion of which corresponds in shape to the conventional circular discs which, throughout the nation, have been adopted by highway authorities as signs indicative of railway crossings.

It is a further object of the invention to provide a crossing signal of the character indicated embodying, in conjunction with suitable flashing lights and illuminated warning elements, means for illuminating the railroad crossing itself. That is to say, powerful lights are provided, the rays of which are directed in such manner that they will illuminate the railroad rails and thus display to approaching drivers, from even a long distance off, two or four streaks of light reflected from the rails and extending across the highway. Whether there are two or four streaks will depend upon whether the track is a single or double track.

These warning streaks of light indicate to the drivers of vehicles the exact location of the railroad crossing, and this is of importance, because there has been a wide variance, in the different states, as to the distance between the warning signal and the railroad crossing. In some states, the signals are placed much closer to the crossing than in others, and drivers who have been accustomed to having a leeway of five or six hundred feet between a warning signal and the actual crossing are startled, and their poise disturbed, when they come to the crossing much sooner than expected, especially at night.

In the accompanying drawings:

Figure 1 is a diagrammatic plan view illustrating the manner of positioning the signals with respect to a grade crossing to illuminate the rails;

Fig. 2 is a front elevation of one of the signals; Fig. 3 is a view like Fig. 2 but with the face of the signal removed to illustrate the motor and lights therein;

Fig. 4 is an edge elevation of the signal of Fig. 2;

Fig. 5 is a horizontal sectional view through the letter-carrying wall of the signal, illustrating the mounting of colored, transparent or translucent buttons therein, and the reflectors associated therewith;

Fig. 6 is a fragmentary view of a modified form of signal casing, and

Fig. 7 is a side elevation of Fig. 6.

Like numerals designate corresponding parts throughout the several figures of the drawings.

Referring now to Fig. 3, it will be seen that the signal of the present invention comprises a round central body portion 5, this round form of signal being adopted to correspond to the form which, under highway practice throughout the nation, is indicative of railway crossings. A cross buck 6 is supported upon the casing 5 and carries reflecting elements or buttons 7. The words "Railroad crossing" are painted upon the arms of the cross buck as shown, and preferably in black, so that in the daytime, these letters can be seen from a long distance. The reflecting crystal buttons 7 conform in their positioning to the outlines of the letters so that at night, the reflected light from automobile headlamps makes these letters stand out as clearly as in the day.

By referring to Fig. 3 it will be seen that the interior of the casing 5 is divided into an upper compartment 8, an intermediate compartment 9, and a lower compartment 10. The compartment 8 houses a suitable signal 11, such as a bell, siren, or the like. The intermediate compartment 9 houses a group of incandescent lamps 12 that are supported in suitable brackets or panels 13. The lower compartment 10 houses an electric motor 14 and flasher 15, of the conventional sign flasher type, the function of which will be hereinafter set forth.

Four of lamps 16, provided with visors 17, depend from the lower portion of the casing 5 and are disposed in an arcuate path so that when these lights are illuminated successively, first in one direction and then in the other, the effect is to simulate the swinging of a lantern across the highway. Preferably, the lenses of these lamps are of red glass, so that apparently a red

lantern is being swung. A suitable standard 18 and base 19 serve to support the structure.

The cover plates 20, hereinafter described, which close the sides of the casing 5, are so formed as to cover all of the sound compartment 8 except an opening 21, which is left to permit the sound to be heard but which is covered by wire screen 22 to prevent the entry of insects. Hoods 23 overlie the opening 21. Those portions 10 of the cover plates 20 which lie opposite the compartment 9 and which consequently are brought opposite the lamps 12, carry translucent or transparent buttons 24.

By referring to Fig. 2 it will be seen that this 15 portion of the cover bears the word "Stop" painted in black upon a yellow or other light-colored background, and the letters of this word are studded and outlined by buttons 24. These buttons are not reflecting buttons; they are 20 transparent or translucent buttons. It is very desirable that the light from all of the lamps 12 be diffused over the whole area of the word "Stop," so that no one button will be more brilliantly illuminated than another. It is to be 25 noted that there are four of the lamps 12, one for each of the letters of the word "Stop," so that each letter will have ample and equal illumination. This, with the shape and nature of the reflecting walls of the compartment 9, insures 30 that the maximum amount of light from the lamps 12 will pass out through the red buttons of the word "Stop."

To this end, the cover plates are, in effect, made as double-wall elements, comprising the 35 outer steel letter face, having openings 20^a formed therethrough for the passage of the protuberant bulbous portions 20^b of the buttons 24. A steel letter back 20^c is held in spaced relation to the wall 20 by suitable rivets and spacers 20^e and 20^f respectively. The bulbous portions 20^b of the buttons are integral with and are carried by cup-like inner portions 20^g.

Sheets of reflecting material 20^h, which may 45 be made of stainless steel, polished chromium, or other non-corrosive and non-oxidizable material, are secured to the steel letter back 20^c and are provided with inturned flanges 20ⁱ which engage inside of the buttons. These flanges surround openings 20^j, through which light may 50 pass directly from the lamps through the bulbous portions of the buttons, and through which light from the lamps, reflected back from the polished reflector on the other side of the lamps, may 55 pass, it being understood that the structure of Fig. 5 is duplicated at each side of the casing 5. That is to say, the cover plates of the casing are, in substance, double-walled elements in which the buttons 24 are mounted and held, to have 60 both direct and reflected light pass therethrough to give the uniform illumination desired.

Those portions of the cover plates 20 below the compartment 10 may be single-walled structures since they carry merely reflecting crystal buttons 25, disposed to conform to the outline 65 of the letters 26, forming the words "On red lite." These words are preferably painted in black to show clearly during the day. The letters of the word "Stop" are also preferably 70 painted in black to show, in like manner, during the day. At night, however, the words "Railroad crossing" and "On red lite" are outlined in white light by the crystal reflecting buttons, while the word "Stop" is outlined in red by the 75 internally illuminated red buttons through which

light intermittently flashes, in conjunction with the apparent swinging of a red lantern.

Flood lights 27 are mounted upon the tops of the casings and are adapted to be turned to direct their rays rearwardly and downwardly. 5 (See Fig. 1—A.) Thus the light rays from the flood lamps do not blind approaching drivers but illuminate the shiny rails A of the railroad track to make these shiny rails stand out as bright streaks across the highway B. 10

The lenses of the flood lights are preferably of amber glass, this amber light being more penetrative of fog than white light.

In the form illustrated in Fig. 3, the lamps 16 are shown as being independently supported by 15 brackets 16^x from the casing 5. In the modification illustrated in Fig. 7, webs 60 are supported by brackets 61 from casing 5, and the lamps 16^b, with their visors 17^a, are supported from these webs. Any desired way may be resorted to of 20 securing the elements of the cross buck, housing, lamp brackets, etc. together, either by flanges and rivets, as indicated with respect to bracket 61 in Fig. 7, or by spot welding, this being merely 25 a matter of engineering choice. Any suitable proportions of parts may be employed. However, I find that if the central circular housing is made about 36" in diameter, it enables me to make the letters of the word "Stop" a full ten 30 inches in height. With this height of letter, the word is readable a full seven hundred feet from the signal.

Therefore, it is to be understood that the invention is not limited to the precise construction set forth, but that it includes within its 35 purview whatever changes fairly come within either the terms or the spirit of the appended claims.

Having described my invention, what I 4 claim is:

1. In a signal of the character described, a housing, a row of lamps therein, a closure for the side of said housing comprising a pair of spaced walls, a plurality of buttons comprising cup-like bodies and bulbous tops, said buttons being made of colored, translucent or transparent material and being of a size to span the space between said spaced walls, the outermost of said walls being pierced for the passage of the bulbous portions of said buttons, said bulbous portions being smaller in diameter than the cup-like bodies of the buttons to thereby provide a shoulder which limits the movement of the buttons outwardly through said outer wall, the inner portions of said buttons bearing upon the inner wall, and said inner wall being pierced to provide openings to permit the entry of light to the interior of said buttons. 5

2. In a signal of the character described, a housing, a row of lamps therein, a closure for the side of said housing comprising a pair of spaced walls, a plurality of buttons comprising cup-like bodies and bulbous tops, said buttons being made of colored, translucent or transparent material and being of a size to span the space between said spaced walls, the outermost of said walls being pierced for the passage of the bulbous portions of said buttons, said bulbous portions being smaller in diameter than the cup-like bodies of the buttons to thereby provide a shoulder which limits the movement of the buttons outwardly through said outer wall, the inner portions of said buttons bearing upon the inner wall, and said inner wall being pierced to pro- 7

vide openings to permit the entry of light to the interior of said buttons, said buttons being disposed to form a warning design.

3. In a signal of the character described, a 5 housing, a row of lamps therein, a closure for the side of said housing comprising a pair of spaced walls, a plurality of buttons comprising cup-like bodies and bulbous tops, said buttons being made of colored, translucent or transparent material and being of a size to span the space between said spaced walls, the outermost of said walls being pierced for the passage of the bulbous portions of said buttons, said bulbous portions being smaller in diameter than the 10 cup-like bodies of the buttons to thereby provide a shoulder which limits the movement of the buttons outwardly through said outer wall, the inner portions of said buttons bearing upon the inner wall and said inner wall being pierced 15 to provide openings to permit the entry of light to the interior of said buttons, and a reflecting material covering the inner face of the inner wall.

4. A structure of the character described com-

prising a casing having open sides, a row of lamps disposed substantially centrally therein and extending thereacross, closures for the sides of said casing, each comprising a pair of walls tied together but lying in spaced relation to each other, a plurality of red transparent buttons, each comprising a cup-like body portion and a bulbous head, the head being of smaller diameter than the body portion and the outer wall being provided with a plurality of openings through 5 which the bulbous portions of the buttons are passed, said buttons spanning the space between said walls and having their inner portions resting against the inner wall, each of said inner walls being covered with reflecting material and 10 each of said inner walls being provided with openings which match with the interiors of said cup-like buttons whereby direct light may pass from the lamps to said interiors and reflected light may pass from the reflecting material carried by the inner wall at the opposite side of the 15 casing to the interiors of said buttons, said buttons being disposed to outline a warning signal. 20
